Primary Examiner — Kendra Leslie Hamilton(74) Attorney, Agent, or Firm — Kirton McConkie; Brian Tucker(57) CLAIM

The ornamental design for a teether, as shown and described.

DESCRIPTION

FIG. 1 is a front perspective view of a teether, showing our new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The broken lines in the drawings depict portions of the teether that form no part of the claimed design.
